[57] CLAIM

The ornamental design for a combined dressing and condiment dispenser, substantially as shown and described.

DESCRIPTION

FIG. 1 is a top, front, and left side perspective view of a combined dressing and condiment dispenser showing my new design;

FIG. 2 is a front elevational view thereof;

FIG. 3 is a right side elevational view thereof;

FIG. 4 is a rear elevational view thereof; and

FIG. 5 is a top plan view thereof.

The bottom of the combined dressing and condiment dispenser is flat and unornamented.

FIG.1.

FIG.2.

FIG.3.

FIG.4.

FIG.5.

UNITED STATES PATENT AND TRADEMARK OFFICE
